UNITED STATES PATENT OFFICE

148,805

DESIGN FOR A GOLF CLUB

Alexander Liolich, Dearborn, and Samuel N.
Liolich, Detroit, Mich.

Application July 29, 1946, Serial No. 132,088

Term of patent 14 years

(Cl. D34—5)

To all whom it may concern:

Be it known that we, Samuel N. Liolich and Alexander Liolich, citizens of the United States, residing at Detroit and Dearborn respectively, in the county of Wayne and State of Michigan, have invented a new, original, and ornamental Design for a Golf Club, of which the following is a specification, reference being had to the accompanying drawing, forming part thereof.

In the drawing:

Figure 1 is an elevation of a golf club embodying our new design.

Figure 2 is an elevation of a golf club taken at an angle of 90° with respect to the elevation of Figure 1 and illustrating the same club.

Figure 3 is a cross-sectional view taken on the line 3—3 of Figure 2.

Figure 4 is a cross-sectional view taken on the line 4—4 of Figure 2.

Figure 5 is a plan of the end of the hand grip portion of the shaft.

In Figures 1 and 2 of the drawing the essen-

tials of the inventive design reside in the portion shown in the full lines and nonessentials in the portions shown in the dotted lines.

We claim:

The ornamental design for a golf club, as shown and described.

ALEXANDER LIOLICH.
SAMUEL N. LIOLICH.
